Design No. 16,981, dated November 9, 1886.

UNITED STATES PATENT OFFICE.

EMMA J. LAWRENCE, OF PHILADELPHIA, PENNSYLVANIA, ASSIGNOR TO THE HARTLEY CARPET AND RUG COMPANY, OF SAME PLACE.

DESIGN FOR A RUG.

SPECIFICATION forming part of Design No. 16,981, dated November 9, 1886.

Application filed August 19, 1886. Serial No. 211,347. Term of patent 3½ years.

To all whom it may concern:

Be it known that I, EMMA J. LAWRENCE, a citizen of the United States, residing in Philadelphia, Pennsylvania, have invented a new and original Design for a Rug, of which the following is a specification.

My design for a rug is shown in the accompanying photographic illustration, which exhibits three-quarters of the rug, the remaining quarter being a duplication of the end border shown.

My design comprises the rectangular center piece, A, having a background contrasting with that of the border B, and the two being separated by a narrow ornamental frame, d. The groundwork of the center piece is "spotted," as it is termed, and on this background are conventional flowers and leaves, as shown. The frame-like margin of the center piece is of such a character as to give the edges of the groundwork a ragged or frayed appearance. The border around the center piece is wider at the ends than at the sides, and has represented on it conventional vine-like leaves and flowers, as shown.

I claim—

The herein-described design for a rug, comprising the rectangular center piece, having a spotted ground, and flowers and leaves thereon, with the border having vine-like leaves and flowers, all substantially as shown and set forth.

30 In testimony whereof I have signed my name to this specification in the presence of two subscribing witnesses.

EMMA J. LAWRENCE.
